(57) **CLAIM**

The ornamental design for a feed towing chain link as shown and described.

DESCRIPTION

1. Feed towing chain link

1.1 : Perspective

1.2 : Perspective

1.3 : Top

1.4 : Bottom

1.5 : Perspective

1.6 : Perspective

The design relates to the outer appearance of feed towing chain link, with a flat elongate arch shape that circumvents an elongate central gate-like cut-out that at its lower side is delimited by a backwards bend connection lip; figs. 1.1-1.4 show a single link; fig. 1.5 shows a chain of the links, whereas fig. 1.6 shows this chain of links as an example inside a partially cut open feeding trough. The broken line portions shown in Reproductions 1.5 and 1.6 illustrate environmental subject matter only and form no part of the claimed design.
